UNITED STATES PATENT OFFICE

THOMAS ARABIJO MARMITO, OF NEW YORK, N. Y.

SPINNING TOP

Application filed October 24, 1931. Serial No. 570,918.

This invention relates to certain new and useful improvements in game apparatus and method of playing the same.

The primary object of the invention is to provide a game apparatus requiring skill in the playing thereof and providing healthful exercise to the participants.

A further object of the invention is to provide game apparatus wherein the accessories include a novel form of spinning top, the game when played indoors being confined within an arena, inclosure or court of novel construction for the protection of spectators.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a perspective view of the inclosure or court in which the game is played, showing the enclosing wall structure surrounded by a screened frame, the spinning plate and the pitcher's plate;

Figure 2 is a detail sectional view of the spinning plate for the top;

Figure 3 is a side elevational view of the novel form of top with the spinning cord wound thereon and illustrated as being of gradually increasing diameter;

Figure 4 is a vertical cross-sectional view of the top, showing a spinning peg in the upper and lower ends thereof with the anchor groove or shoulder for the spinning cord;

Figure 5 is a side elevational view of the top in inverted position as shown in Figure 3, with the spinning cord wound upon the same end of the top;

Figure 6 is a vertical cross-sectional view of the top in inverted form as illustrated in Figure 5; and

Figure 7 is a perspective view of the dipper employed for transporting the top during the playing of the game.

The game is adapted to be played indoors or outdoors, and when played indoors, the game is confined within an enclosure or court, such as illustrated in Figure 1, although it

is to be understood that such a court structure may be resorted to when the same is played outdoors with the court surrounded by a grandstand or seating arrangement. The court includes side walls 11 and end walls 12 and 13 and entrance to the court is by way of the gate openings 14 in the side and end walls 11 and 13, each gate opening 14 facing a guard wall 15 inwardly of the side and end walls 11 and 13 with the opposite ends thereof curved as at 16 and directed toward the side and end walls, but spaced therefrom to permit the entry and exit of the players of the game. To guard the spectators, a superposed screen frame is mounted upon the side and end walls of the court and preferably includes a rod frame structure 17 carrying a net of screen 18, while screen sections 19 inclined as illustrated extend from the upper edges of the guard walls 15 to the upper sides of the screened frame 17.

Spinning tops are used in the playing of the game and as shown in Figures 1 and 2, a plate 20 upon which the tops are adapted to be spun is set into the ground within the court, spinning tops being represented upon the plate 20 by the reference numeral 21. The spinning plate 20 may be constructed of any suitable material, such as hard rubber or the like, a second plate 22 being positioned within the court adjacent the end wall 13 to be known as the pitcher's plate. The game may be played by two persons, or two teams comprising the same number of players, one player or team preferably using the side gate of the court while the other player or team use the end gate. In the playing of the game, the members of one team enter through the side gate and spin their tops upon the plate 20 and thereafter withdraw to a safe distance or make their exit through the side gate to stand within the guard wall 15 and view the proceedings. The members of the other team stand upon the pitching plate 22 and the object of the game is for each player upon the pitching plate 22 to strike one of the spinning tops 21 to remove the same from the spinning plate 20 and if possible, either stop the top 21 from spinning or to mate-

rially reduce the speed of rotation thereof. In the event that the top 21 dislodged from the spinning plate 20 ceases to spin and the pitcher's top continues to spin, the owner of the top 21 loses a point and the opponent gains a point. After the top 21 has been dislodged from the spinning plate 20, the owner thereof, in the event that the top 21 continues to spin, uses the dipper 23 shown in Figure 7 for raising the top from the ground and he may carry the spinning top upon the dipper to a safe position where the same will not be struck by a thrown top of a player on the opposing team, while the player who has dislodged the top 21 from the spinning plate 20 also transports his top in a dipper 23 and the top which spins the longest wins a point in the game score.

An improved form of spinning top and spinning cord associated therewith is illustrated in Figures 3 to 6, the design of this top permitting the same to spin for at least ten to fifteen minutes when thrown by an experienced player, the top being double ended with the spinning cord adapted to be wound upon one end only while the top may be spun upon either end. The top 21 comprises a body portion 24, the diameter of which is substantially equal to the height of the top so as to position the center of gravity substantially midway opposite ends of the top. From the transverse center line of the top, the body portion 24 gracefully tapers as at 25 and 26 in opposite directions to provide opposite cone ends 27 and 28 with a spinning peg 29 anchored in each end 27 and 28 and retained therein by barbs 30, only a relatively short section of the spinning peg 29 projecting outwardly of the conical ends 27 and 28. The tapering side 25 of the body portion of the top 24 adjacent the conical end 27 is provided with an annular depression 31 defining an abutment shoulder 32 to receive one end of the top spinning cord 33 which acts to prevent the wound cord from slipping upon the body of the top. The end of the top outwardly of the depression 31 is annularly enlarged to compensate for the cut-away portion forming the depression and acts to balance the top and locate the center of gravity substantially midway the ends of the top to increase the spinning period of the top. The winding cord 33 as illustrated in Figure 3 is of gradually increasing diameter throughout the length thereof, the smaller end being wound upon the tapering side 25 of the top body, while the free larger end thereof is looped as at 34 to provide a finger grip. The spinning cord 33 is always wound upon the same end of the top body 24, the smaller end of the cord being first placed in the groove 31 in engagement with the abutment shoulder 32 and the winding cord is of a length to have the convolutions thereof when wound on the top body to be placed substantially midway the

opposite peg ends of the top and with the cord so wound thereon, the top may be spun upon either peg end 29. By placing the smaller end of the cord into initial winding engagement with the top, the number of convolutions of the cord are increased, friction between the cord and top is increased, while the larger diameter of cord is present for hand manipulation in the spinning of the top. By the use of a cord of this character with the form of top disclosed, increased velocity is imparted to the spinning movement of the top, further enhanced by the balanced top having its center of gravity located substantially midway its ends.

From the above detailed description of the invention, it is believed that the construction of the apparatus and accessories as well as the method of playing the game will at once be apparent. Although no specific dimensions of the playing field defined by the court wall have herein been mentioned, it is to be understood that the area of the playing field must be such that the pitching plate may be spaced from the spinning plate a sufficient distance to require skill by the player throwing the top missile toward a spinning top on the spinning plate to strike the same and that the area of the playing field must be such that opponents of the two teams may move freely over the field in approaching their spinning tops to raise the same upon the dippers.

While there is herein shown and described the preferred embodiment of the invention, it is nevertheless to be understood that minor changes may be made therein without departing from the spirit and scope of the invention as claimed.

I claim:

1. A device comprising a spinning top having a spinning peg at opposite ends with opposite ends of the top tapered and the transverse diameter of the top being substantially equal to the height of the top, a weight provided integrally at one of said ends for keeping the device upright when being spun and tapering means for spinning said top.

2. A device comprising a spinning top having a spinning peg at opposite ends, the side wall of the top adjacent one end being annularly grooved to provide an abutment shoulder for a spinning cord, and said spinning cord being of gradually increasing diameter in the direction of length thereof with the smaller end of the cord initially wound on the top for increased gripping action and to impart increased velocity to the spinning of the top.

3. A cord for spinning a top, said cord being tapered gradually from one end to the other, the smaller end being initially wound on the top.

In testimony whereof I affix my signature.

THOMAS ARABIJO MARMITO.
